CLAIM

The ornamental design for a filter for use on water conduits, as shown and described.

DESCRIPTION

FIG. 1 is a front elevational view of the filter for use on water conduits showing my new design;
FIG. 2 is a rear elevational view thereof;
FIG. 3 is a left side elevational view thereof;
FIG. 4 is a right side elevational view thereof;
FIG. 5 is a top plan view thereof on an enlarged scale;
FIG. 6 is a bottom plan view thereof, on an enlarged scale; and,
FIG. 7 is an isometric view thereof showing my filter being typically used in a transparent housing.
The broken line drawing of a water conduit in FIG. 7 is for illustrative purposes only and forms no part of the claimed design.
